DESIGN FOR A CUSHION SUPPORT FOR FURNITURE

Harry Phillips, Greenwich, Conn.

Application February 21, 1941, Serial No. 99,167

Term of patent 3½ years

To all whom it may concern:

Be it known that I, Harry Phillips, a citizen of the United States, residing at Greenwich, Fairfield County, State of Connecticut, have invented a new, original, and ornamental Design for a Cushion Support for Furniture, of which the following is a specification, reference being had to the accompanying drawing, forming part thereof.

Fig. 1 is an edge view of a cushion support for furniture showing my new design.

Fig. 2 is a top plan view and

Fig. 3 is a cross-sectional view as on the line 3—3 of Fig. 2.

The characteristic feature of my design resides in the three uniformly spaced grooves on the conical face or side walls, comprising a V-shaped upper groove and a pair of rectangular grooves in combination with the relatively short cylindrical base, all as shown.

I claim:

The ornamental design for a cushion support for furniture, substantially as shown and described.

HARRY PHILLIPS.
